UNITED STATES PATENT OFFICE.

GEORGE KEITH, OF LONDON, ENGLAND, ASSIGNOR TO JAMES KEITH & BLACKMAN COMPANY, LIMITED, OF LONDON, ENGLAND, A CORPORATION OF GREAT BRITAIN.

GAS BURNER.

1,413,661.

Specification of Letters Patent. Patented Apr. 25, 1922.

Application filed September 15, 1921. Serial No. 500,730.

To all whom it may concern:

Be it known that I, GEORGE KEITH, a subject of the King of the United Kingdom of Great Britain and Ireland, and residing at 5 27 Farringdon Avenue, London, England, have invented a certain new and useful Improvement in Gas Burners, of which the following is a specification.

This invention relates to tubular gas burners of the type divided into two chambers the outer one of which has one or more longitudinal slots and at the inlet end of the inner one of which is arranged a valve adapted to allow part of the gaseous mixture admitted to said chamber to pass direct to the outer chamber and thence to the outlet or outlets, without passing through the inner chamber.

According to the invention the injector body or casting, which is screwed or otherwise fitted on to the end of the burner tube, is bent at a suitable angle or inclined to the axis of the burner tube, being preferably bent downwards, so as to clear the valve 25 spindle which projects to the exterior of the burner tube, permitting the control of the distribution of the gas while the gas is actually burning; the bending downwards of the body of the injector serving also to reduce the liability to fouling of the mixture 30 by oven products passing out of the usual inspection doors when opened for observation.

In the accompanying drawings Fig. 1 is a vertical section of part of a gas burner according to the invention in which the valve is constituted by a push and pull sleeve. Fig. 2 shows a modification in which the valve is constituted by a rotary sleeve. 40 In the form shown in Fig. 1 the valve spindle 3 is disconnectible from the valve or sleeve 4 by turning up the inner end of the spindle 3 which passes through a hole in an extension 5 of the sleeve. The outer end

of the valve spindle, which is screw-threaded, is protected by an extension 6 of the gland which permits operation of the spindle by a removable key 7.

In the form shown in Fig. 2 the inner end of the spindle 8 is split so as to form a T 50 head 9 which engages with cross-cuts in the end of the sleeve 10 and is retained in engagement by means of a spring 11 pressing it inwards. In this form also the outer end of the spindle 8 is protected from tampering 55 by an extension 12 of the gland, the outer end of the spindle 8 being squared or suitably shaped so as to be operable by a key.

In both forms the injector body or casting 13 is bent downwards. 60

With the constructions described and shown the distribution of the gas may be controlled while the gas is actually burning.

With the injector body bent downwards, as indicated, there is less liability to fouling 65 of the mixture by oven products which pass by the usual inspection doors and would otherwise enter the inlet of the injector.

I claim:—

A tubular gas burner comprising an inner 70 chamber and an outer chamber, said outer chamber being slotted longitudinally, a valve at the inlet end of said inner chamber, said valve adapted to allow part of the gaseous mixture admitted to said inner chamber to 75 pass direct to the outer chamber, said valve controllable from outside the burner, and an injector for feeding said burner, the body of said injector being inclined to the axis of said burner. 80

In testimony whereof I have signed my name to this specification in the presence of two subscribing witnesses.

GEORGE KEITH.
